UNITED STATES PATENT OFFICE.

JOHN P. WAHLSTROM, OF MINNEAPOLIS, MINNESOTA.

SELECTIVE CIRCUIT-CLOSER.

1,327,505.

Specification of Letters Patent.

Patented Jan. 6, 1920.

Application filed October 6, 1917. Serial No. 195,103.

To all whom it may concern:

Be it known that I, JOHN P. WAHLSTROM, a citizen of the United States, residing at Minneapolis, in the county of Hennepin and State of Minnesota, have invented new and useful Improvements in Selective Circuit-Closers, of which the following is a specification.

This invention relates to circuit-closers for use particularly in automatic fire alarms, and more especially to those having fusible elements thermally operated; and one object of the same is to produce a device of this character having thermal elements which may be selectively employed by the user so as to cause the circuit to be automatically closed at either a relatively low or a relatively high but always abnormal degree of heat.

Another object is to provide improved means for permitting replacement of the cartridge.

Other objects will appear in the following specification which contains a detailed description of the preferred construction of this circuit closer, reference being had to the drawings wherein—

Figure 1 is a front elevation of the complete apparatus set with the terminals out of contact and held in that position by both thermal elements.

Fig. 2 is a similar elevation with the parts in position showing the terminals closed, the cartridge holder turned downward and the fuse as having been melted.

Fig. 3 is a horizontal section on the line 3—3 of Fig. 1, and Fig. 4 is a vertical section on the line 4—4 thereof.

Fig. 5 is an enlarged sectional detail of the cartridge holder, showing a cartridge as slightly removed therefrom.

Fig. 6 is a perspective detail of a fuse on an enlarged scale showing the supporting bracket to which one end of the fuse is attached and a fastening screw through its other end.

The numeral 1 designates a base which may be a block of wood, or of porcelain, fiber, or the like, about three inches square, and which is to be secured to a wall or other upright support by any suitable means not

necessary to illustrate. I have shown binding posts 2 and 3 near the lower end of this base, and wires leading from them, and when this device is used as a circuit closer in an automatic fire alarm system, these wires will lead through a source of electric energy to an annunciator having an appropriate drop to designate the apartment in which this device is located, and also through a bell or other signal which is actuated to sound an alarm at the time the circuit is closed. However, details of the wiring and the signal mechanism form no part of the present invention and are therefore not illustrated. I have spoken of the same merely to explain the intended use to which this circuit closer is to be put. I may say here that if the circuit closer is set up in an apartment, a hotel room, or an office, it is desirable that it shall act to close the alarm circuit at a relatively low temperature such as 180° F.; whereas if the device is set up in a boiler room for instance and where the temperature is always higher, it will be set so as to act at a relatively high temperature as 155° F. An important feature of the invention is the structure of the instrument which permits the operator to set it for action selectively at either low or high temperature, but of course always at a temperature considerably above normal and which will never be reached unless a fire should occur. No matter what choice the operator makes, most of the elements of the structure are in use. From the post 2 a strip 4 rises to and makes electrical connection with a plate 5 which carries the cartridge holder best seen in Fig. 5, and also carries a forwardly projecting rigid pin 6 which constitutes one of the terminals. On the plate below the pin is a screw 7 which projects forward, and on this screw is loosely mounted the head 8 of a tubular T-shaped element, held removably and adjustably thereon by a nut 9 on the forward end of the screw. The stem 10 of said element constitutes a socket for receiving a fusible cartridge, the latter consisting of a wooden plug 11 of a size to enter the socket, and a soft outer end 12 made up of a mixture of soap stone, pumice-stone, and wax or equiv-

alent binder—the composition being such that it will melt or become softened at about 130° F. When in active position as seen in Fig. 1, the stem 10 stands horizontally and is so held by tightening the nut 9, and the cartridge will not of course fall out of the socket; but when the nut is loosened the cartridge holder assumes position best seen in Fig. 2, the used cartridge drops out and 10 a new one may be inserted and the device reset at any time.

From the post 3 rises a strip 14 extending past the plate 5 and connected at its upper end with a right-angular plate 15 whose outer 15 wardly projecting leaf is secured to one arm of an inverted U-shaped spring 16, the other arm of the spring depending to a point where its expansion throws it into normal contact with the outer end of the cartridge, 20 and the front edge of this arm is preferably notched as shown at 17. The lower end of the outer leaf of spring 16 is bent into a horizontal lip 18, and pivoted beneath the same at 19 is one end of the other terminal 26 whose rear edge is preferably provided with 25 a notch 27 as best seen in Fig. 3 and whose free end overlies the terminal 6 but may only contact therewith when the two notches 17 and 27 register. For drawing the edge 30 of the terminal 26 toward the front edge of the free arm of the spring 16, a spring is employed; and while I may use any approved form of spring, I have shown the same herein in the shape of a long leaf 20, 35 provided on its upper end is a bracket 21 mounted on the base, and having its lower end bent forward and reduced in the form of a finger 22 which enters a hole or eye 23 in the terminal 26—all as best seen in 40 Fig. 4. The tendency of this leaf spring is to swing the terminal inward on its pivot 19 and throw its free end into contact with the terminal 6, and this tendency is resisted by the contact of the rear edge of the 45 terminal 26 with the bottom of the notch 17 in the spring 16, whereas said leaf spring is permitted to close the circuit when the two notches register as stated above. One device for holding the notches out of registration is the fusible cartridge when carried by 50 its holder as seen in Fig. 1, because this cartridge is of such length that it holds the U-spring 16 compressed slightly so that the notches cannot register.

Secured to the face of the base is a bracket 55 80, and centrally pivoted at 31 to said bracket is a rock lever 32, its lower end adapted to contact with the free arm of the main spring 16 at a point just above the notch therein. The numeral 33 designates another bracket, and 34 is a fuse whose extremities are removably connected by screws 35 and 36 with the bracket 33 and the upper end of the rock lever 32 respectively. This

fuse is of soft metal or a composition of 65 metals, or it may be made of two pieces of metal overlapped and soldered together by fusible material as best seen in Fig. 6. At any rate, it is intended to melt or become softened or parted by the strain thrown 70 upon it, when a temperature of 155° F. is reached. Obviously the fuse may be replaced by another, by withdrawing the screws 35 and 36 and inserting them through the eyes at the ends of the new fuse, and obviously the fuse can be thrown entirely out of use by withdrawing one of said screws and turning or swinging the fuse aside on the other screw. 75

Fig. 1 shows both thermal elements in 80 use and the parts of the device set. When the temperature rises to 130° the cartridge will melt but the main spring is yet held compressed by the rock lever. When the temperature reaches 155° the fuse will melt 85 and the expansion of the main spring permits its free arm to move to the left so that its notch comes into register with the notch in the terminal 26, and the spring 20 draws on the latter to throw its free end into contact with the terminal 6, and this closing of the circuit may perform any desired service. When it is desired to have the instrument act at the higher temperature it may be well to either remove the cartridge or swing the 90 cartridge holder aside. When it is desired to have the instrument act at the lower temperature, the screw at one extremity of the fuse will be removed and the fuse turned aside, whereas the cartridge must be used. 95 Therefore the device permits the operator a certain choice in selection of the temperature at which he wishes the circuit closed, and this in addition to the fact that he might have yet softer or more easily fused cartridges and yet harder or less easily melted fuses so as to amplify the range of temperatures within which the circuit would be closed. Having once acted, the device is 100 reset in an obvious manner. 110

I claim:

1. In a selective circuit closer, the combination with fixed and movable terminals, a spring throwing them normally into contact, an element which in one position prevents the action of said spring, of thermal members fusible at different temperatures, means for turning one into contact with the element to hold it in said position, a rock lever, a bracket, and means for connecting the other element with said bracket and rock the lever to hold one arm of the latter in contact with the element and hold the element in said position. 115

2. In a selective circuit closer, the combination with fixed and movable terminals, a spring throwing them normally into contact, an element which in one position pre- 120 125

vents the action of said spring, of a cartridge fusible at one temperature, a movable holder for supporting the cartridge with one end in contact with the element to hold it in said position when desired, a centrally pivoted rock lever having one end in contact with the element, and a fuse fusible at another temperature and adapted to connect the other end of said lever with a fixed point at will, for the purpose set forth.

3. In a selective circuit closer, the combination with a fixed terminal, a movable terminal pivoted at one end to the support and having a notch in its rear edge, a spring drawing its free end normally toward the fixed terminal, and a spring retainer whose free arm stands behind the movable terminal; of thermal members fusible at different temperatures, and means for throwing them selectively or jointly into connection with said free arm to hold it out of register with said notch.

4. In a selective circuit closer, the combination with a fixed terminal, a movable terminal pivoted at one end to the support and having a notch in its rear edge, a spring drawing its free end normally toward the fixed terminal, and a spring retainer whose free arm stands behind the movable terminal; of a thermal member fusible at one temperature, means for turning it into contact with the free end of said arm when desired, a second thermal member fusible at another temperature, a pivoted lever whose tip bears on said arm, and means for connecting this lever with a fixed point by said second member when desired, the use of either or both members holding said arm out of registry with the notch in the movable terminal.

5. In a selective circuit closer, the combination with a base, and a fixed terminal carried thereby, a rigid angular member mounted on the base and having an outwardly projecting leaf, of a U-shaped spring having one arm attached to said leaf and its lower end bent into a horizontal lip, a movable terminal pivoted at one end to said lip and having a notch at its rear edge, and a spring bearing its free end normally toward the fixed terminal but supported therefrom by the free arm of the U-shaped spring and located behind the pivoted terminal across the same, said free arm provided in its front edge with a notch at the point of crossing, the depth of the two notches being such that when they register the terminals may contact, a thermal member fusible at one temperature, means for throwing it into contact with the lower end of the free arm of said U-shaped spring when desired to hold said notches out of registry, a rock lever having one end contacting with said arm above the movable terminal, a second

thermal member fusible at another temperature, and means for connecting this member with a fixed point and said lever when desired to hold the lever in position to also hold said notches out of registry.

6. In a circuit closer, the combination with a base, a fixed terminal carried thereby, a rigid angular member mounted on the base and having an outwardly projecting leaf, of a U-shaped spring having one arm attached to said leaf and its lower end bent into a horizontal lip, a movable terminal pivoted at one end to said lip and having a notch at its rear edge, a spring bearing its free end normally toward the fixed terminal but supported therefrom by the free arm of the U-shaped spring, which stands behind the pivoted terminal across the same, said free arm provided in its front edge with a notch at the point of crossing, the depth of the two notches being such that when they register the terminals may contact, thermal members fusible at different temperatures, and means for selectively throwing them into use to hold said notches out of register.

7. In a circuit closer, the combination with a base, a fixed terminal carried thereby, a rigid angular member mounted on the base and having an outwardly projecting leaf, of a U-shaped spring having one arm attached to said leaf and its lower end bent into a horizontal lip, a movable terminal pivoted at one end to said lip and having a notch at its rear edge, and a spring bearing its free end normally toward the fixed terminal but supported therefrom by the free arm of the U-shaped spring, which stands behind the pivoted terminal across the same, said free arm provided in its front edge with a notch at the point of crossing, the depth of the two notches being such that when they register the terminals may contact, a screw projecting from said base and having a nut, a holder movably mounted on the screw beneath this nut, and a fusible plug removably inserted in the holder and adapted by the turning of the latter to be set in contact with the free end of said arm to hold said notches out of registry.

8. In a circuit closer, the combination with a base, a fixed terminal carried thereby, a screw also carried thereby, a nut on the screw, a movable terminal having one end pivotally connected with the base, a spring tending to swing its free end normally into contact with the fixed terminal, and a spring attached to the base and having an arm passing behind the movable terminal, this terminal and arm having notches in their contacting edges which when in register permit the terminals to contact; of a T-shaped tubular holder whose head is mounted on said screw under its nut, and a fusible car-

tridge removably inserted in the stem of the holder and adapted to be turned into contact with the free end of said spring to hold said notches out of register.

5. 9. In a circuit closer, the combination with a base, terminals, means throwing them normally into contact, and a spring-held element normally permitting said means to act; of a T-shaped tubular holder, means for

movably mounting its head on said base, and 10 a fusible cartridge removably carried in its stem and adapted to be turned into contact with said element to hold it out of normal position and to hold the terminals out of contact with each other. 15

In testimony whereof I affix my signature.

JOHN P. WAHLSTROM.
